Inventor:

Clarence E. Ogden,
By Arthur S. Ewald,
Attorney.

UNITED STATES PATENT OFFICE.

CLARENCE E. OGDEN, OF CINCINNATI, OHIO.

ELECTRIC CONTROLLER.

1,316,320.

Specification of Letters Patent. Patented Sept. 16, 1919.

Application filed December 26, 1918. Serial No. 268,300.

To all whom it may concern:

Be it known that I, CLARENCE E. OGDEN, a citizen of the United States, resident of Cincinnati, county of Hamilton, and State 5 of Ohio, have invented certain new and useful Improvements in Electric Controllers, of which the following is a full, clear, and exact description, reference being had to the accompanying drawings, forming a part 10 of this specification.

My invention relates to electric controllers and has for its object the provision of means whereby the operator of such a controller is prevented from reversing the current 15 without first bringing the controller mechanism to a dead stop at the "off" position.

In the operation of electric controllers, such as are designed for commercial trucks, and other similar purposes, it is necessary, 20 in order that the controller and other mechanism be kept from injury, that the flow of current be not reversed without first bringing the controller to a definite or dead pause at the "off" position. When this is 25 not done there is great danger of burning out the electrical connections, and various devices have consequently been proposed for the elimination of this danger. The present invention provides simple and inexpensive 30 means in connection with the controller lever whereby a definite and positive stop of the lever is rendered imperative before the same can be moved in the direction for bringing the reverse contacts into engagement.

35 Other objects of the present invention will appear from the following detailed description thereof.

In the drawings:—

40 Figure 1 is a side elevation of the upper portion of an electric controller constructed in accordance with this invention.

Fig. 2 is a top view of the same.

Fig. 3 is a longitudinal section of the controller arm and slider, in accordance with 45 this invention.

The numeral 1 indicates the upper plate of the casing of an electric controller of ordinary design, the same being provided with a center boss 2, having the usual bearing 50 for the controller drum shaft 3. Secured to the upper end of the shaft is a lever 4 provided with an operating handle 5, in accordance generally with the usual construction.

55 The plate 1 is provided with the depress-

sions 6 in which a spring pressed ball 7 in the lever is arranged to engage for indicating, and frictionally securing the lever in, desired positions. In order that the operating lever 4 may be brought to a definite 60 stop in the "off" position, the plate 1 of the casing is provided with lugs 8 and 9 unequally distanced from the axis of the shaft 3, and disposed on different radii, as clearly shown in Fig. 2 of the drawing. 65

The under side of the arm 4 is provided with bosses 10 between which a bar or slider 11 is slidably mounted, plates 12 being secured to the bosses 10 under the slider 11, in order to retain the same in position. The 70 slider 11 is provided with a lug 13 arranged to engage either of the lugs 8 or 9, in accordance with the position in which the slider is placed, one or the other of said lugs being at all times in the path of the lug 13. 75 In order that the slider may be held in proper position to engage either the lug 8 or the lug 9, the same is provided with a spring pressed ball 14, which is arranged to engage in recesses 15 in the underside 80 of the arm. The outer end of the slider 11 is provided with a finger piece 16 for the operation thereof.

The operation of the device will be apparent from the foregoing description 85 thereof to those familiar with the art to which the same appertains. When the slider is in forward position, in which it is shown in Fig. 1, the operating arm 4 may be moved to the right for making the "forward" contacts. When it is desired to reverse, the lever is brought to neutral position where it is stopped by the engagement of lug 13 against the lug 9 on the casing. The slider 11, is then pushed back until the lug 13 95 which passes to the left of lug 8, clears the lug 9, after which the lever may be moved to the left to make the "reverse" contacts. Before the controller lever can be moved to make the "forward" contacts again, the 100 reverse operation of the slider must be performed when the lever is in neutral position before it can be advanced further to make the "forward" contacts. It will thus be seen that in order to reverse in either direction 105 it is absolutely essential that a positive stop be made in neutral position, for the reason that it is impossible to set the slider in advance of reaching that position, as doing so would merely cause it to engage the lug 8 110

or 9 other than the one which it should normally engage when moving in the direction of operation. Injury to the controller or motor mechanism by a too quick reversal is thus entirely overcome.

Having thus described my invention, what I claim as new and desire to secure by Letters Patent, is:—

1. In an electric controller, having a casing and an operating lever, a bar slidably mounted on said lever, a lug on said bar and two lugs on said casing, said lugs being unequally distanced from the axis of said lever, so that one or the other thereof is at all times in the path of travel of the lug on said bar during the operation of said lever, and said lugs on said casing being disposed on different radii from the axis of said lever so that the lug on said bar may by the sliding thereof be moved from

one side of one of the lugs on said casing to the opposite side of the other lug thereon.

2. In an electric controller, having a casing and an operating lever, a bar slidably mounted on said lever, a lug on said bar, two lugs on said casing, said lugs being unequally distanced from the axis of said lever, so that one or the other thereof is at all times in the path of travel of the lug on said bar during the operation of said lever, and said lugs on said casing being disposed on different radii from the axis of said lever so that the lug on said bar may by the sliding thereof be moved from one side of one of the lugs on said casing to the opposite side of the other lug thereon, and means for securing said bar in desired position on said lever.

CLARENCE E. OGDEN.
